JOHN H. QUINN, OF PATERSON, NEW JERSEY, ASSIGNOR TO QUINN BROTHERS, A FIRM CONSISTING OF ROBERT E. QUINN AND SAID JOHN H. QUINN, OF PATERSON, NEW JERSEY.

ANTIFREEZING VALVE.

1,263,107.

Specification of Letters Patent.

Patented Apr. 16, 1918.

Application filed August 12, 1916. Serial No. 114,499.

To all whom it may concern:

Be it known that I, JOHN H. QUINN, a citizen of the United States, residing at Paterson, in the county of Passaic and State 5 of New Jersey, have invented certain new and useful Improvements in Antifreezing Valves, of which the following is a specification.

This invention relates to valves for so 10 called "hopper" closets of the kind constructed so that the water remaining in the casing of the valve and in the pipe which leads therefrom to the closet will drain off when the flow through the valve is stopped 15 thereby to prevent freezing taking place within said casing and the pipe.

The principal object of the invention is 20 to provide a valve of this type which shall possess all of the following desirable qualities, to wit, simplicity, strength, durability and compactness of construction, efficiency 25 and reliability in operation, adaptability for use reversibly, and capability of perfectly draining itself when the water is cut off.

25 In the accompanying drawings, in which the invention is fully illustrated,

Figure 1 is a front elevation, partly in 30 section in a vertical plane substantially central of the three passages of the valve casing;

Fig. 2 is a plan, the couplings being removed;

Fig. 3 is a view mainly in transverse central vertical section;

Fig. 4 shows the valve-body and its operating spindle partly in section and partly in elevation; and

Fig. 5 shows these parts in plan, disconnected from each other.

40 The casing *a* of the valve is formed with a suitable base or standard *b* and it has a central chamber *c* with which communicate three passages, *d*, *e* and *f*, the passages *d* and *e* being horizontal and aligned with each 45 other and the passage *f* vertical; said passages are formed in three corresponding arms *d'*, *e'* and *f'* of the casing, and these are externally threaded, as shown, for the 50 reception of the unions *d''*, *e''* and *f''* whereby the couplings *g*, *h* and *i*, threaded at their outer ends for the attachment thereto of the supply, waste and outlet pipes (not shown) in the usual manner and shaped 55 preferably at their inner ends to produce ground joints *g'*, *h'* and *i'* with the pas-

saged arms *d'*, *e'*, and *f'*, are connected with said arms.

At *d'''* and *e'''* the passaged arms *d* and *e* are reduced so as to form both a bearing and a seat in each instance for the valve 60 (to be described), leaving an enlargement to form a valve chamber between each such bearing and seat *d'''* (*e'''*) and the adjoining coupling *g* (*h*); the valve chambers are designated *d''''* (*e''''*). 65

In the bearings *d'''* and *e'''* is guided to move rectilinearly and without transverse play the said valve. This is shown best in Figs. 4 and 5 and consists of the cylindrical body *j* fluted or channeled longitudinally, 70 except at its extreme ends, and having its said ends recessed as seen best in Fig. 4, and Fuller or equivalent washers or valves proper *k* fitted thereto and secured in place by screws or the like *l*, having play in the 75 valve chambers *d''''*, *e''''*. Movement of the valve rectilinearly brings one or the other of its washers against a seat *d'''*, *e'''*, in which position the flow through one passage will be obstructed while that through 80 the other may proceed because the fluted portion of the valve body *j* penetrates the corresponding bearing *d'''* (*e'''*). The valve is reversible end for end. Either of the couplings *g* and *h* may be attached to 85 the supply pipe, as the requirements of the application of the device in the plumbing may demand; and in either case the pressure of the supply normally tends to seat the valve so as to stop the flow from the supply. 90

For operating the valve proper I provide the spindle *m* having an enlargement *n* at one end formed with an offset arm *n'*, making the spindle in effect a crank; the other end of the spindle or crank is squared and adapted to receive a lever, preferably weighted, designated *o*, to which an operating wire or chain *p* may be attached. The arm *n'* is received by a cross-cut recess *q* formed vertically in the body *j* of the 100 valve. The bottom of the recess and the outer face of the arm *n'* are flat and bear squarely against each other, and since the arm reaches below the central horizontal plane of the valve in contact with the bottom of its recess the valve is prevented by the crank from turning in its bearing in the valve casing. 105

To afford a substantial bearing for the 110 crank *m* and permit the same to be readily

assembled with and detached from the other parts, I screw into the threaded hole *r* formed in the back of the casing *a* so as to enter its central chamber *c* substantially central thereof a bushing *s*, which may have 5 screwed onto its outer end a stuffing-box or gland *t* containing packing *u*.

In the normal position of the moving parts, the valve closes off the supply of water, which in the present instance is assumed 10 to be admitted through coupling *g*, the weighted lever *o* and the water pressure holding the right-hand washer *k* seated. When the lever is raised the valve will be 15 shifted to the right, unseating the right-hand and seating the left-hand washer *k*, so that the water passes through the central chamber *c* and out through coupling *i* toward the closet. On the lever being allowed 20 to fall, the valve is returned to its normal position, seating the right-hand and unseating the left-hand washer *k*, so that the water is again cut off, and such water as remains in the valve casing *a* and the outlet 25 pipe connected to coupling *i* drains off through coupling *h*, leaving them entirely free of water.

To prevent the washers *k* from being subjected to undue pressure when the valve 30 proper is moved to either of its limits the arm *n'* of the crank, as it pushes against one side of the slot *q*, is adapted ultimately to impinge against the other side at the corner *v*.

35 It will be apparent that my construction not only produces a valve structure that is perfectly self-draining in character, but that, chiefly due to the straight-through arrangement of the supply and waste passages, with the outlet passage arranged to bisect their line midway between them, the device may be made symmetrical in form 40 and reversible and may be produced with the minimum of working parts and with 45 certain assurance that they will operate to best advantage.

Having thus fully described my invention, what I claim and desire to secure by Letters Patent is:

50 1. In combination, a casing having a cen-

tral chamber, alined supply and waste passages communicating with said chamber at opposite sides thereof and an outlet passage also communicating with said chamber between the points of communication therewith of the supply and waste passages, said supply and waste passages each having a relatively inward reduced portion *d'''* and a relatively outward enlargement forming a valve-chamber, a valve movable back and forth in and longitudinally of said supply and waste passages and including a fluted cylindrical valve body snugly fitting said reduced portions and two valves proper respectively arranged in said valve chambers 55 and adapted to alternately seat relatively inwardly and close said reduced portions and thereby seal one and leave open the other of said supply and waste passage when the valve is moved back and forth, and means 60 to move the valve.

2. In combination, a casing having a central chamber, alined counterpart cylindrical supply and waste passages communicating with said chamber at opposite sides thereof 75 and an outlet passage also communicating with said chamber between the points of communication therewith of the supply and waste passages, a valve arranged to reciprocate longitudinally in and of said passages 80 and including a cylindrical valve-body snugly fitting each passage and two valves proper, one for each passage, on said body, a bearing bushing *s* removably arranged in said casing with the bearing axis thereof 85 penetrating said chamber and at right angles to the line of reciprocating movement of the valve, said valve having a recess therein laterally open toward the bushing, and an operating crank journaled in the 90 bushing with its axis concentric with the axis of the bushing and having an arm within said chamber and arranged in said recess, the bottom of the recess being flat and the crank arm having a flat face perpendicular 95 to the axis of movement of the crank and bearing flat against said bottom of the recess.

In testimony whereof I affix my signature.

JOHN H. QUINN.
